UNITED STATES PATENT OFFICE.

ALEXANDER ROSS AND CYRUS ABROM McALLISTER, OF ROCHESTER, NEW YORK, ASSIGNEES OF ONE-THIRD TO BENTON F. BLACKALL, OF SAME PLACE.

AUTOMATIC SPRINKLER.

SPECIFICATION forming part of Letters Patent No. 368,425, dated August 16, 1887.

Application filed February 2, 1887. Serial No. 226,210. (No model.)

To all whom it may concern:

Be it known that we, ALEXANDER ROSS and CYRUS A. McALLISTER, citizens of the United States, residing at Rochester, in the county of Monroe and State of New York, have invented certain new and useful Improvements in Automatic Sprinklers; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The invention relates to an automatic sprinkler which is adapted for use in extinguishing fire; and its object is to provide an efficient device that will be brought promptly into action under particular conditions, but 20 will certainly remain inoperative unless said conditions exist; and it consists in the several matters hereinafter described, and particularly pointed out in the claims.

In the accompanying drawings, which form 25 a part of this specification, Figure 1 represents a side view of the sprinkler, showing the positions of the several parts when the valve is closed against its seat at the end of the nozzle, the positions occupied when the valve is open 30 being indicated in dotted lines. Fig. 2 represents a bottom view of the combined valve and distributor, showing its hub provided with an opening rectangular in cross-section. Fig. 3 represents a plan view of the upper side of the 35 valve and distributor. Fig. 4 represents the upper end of the screw-body shaped to fit the opening in the hub. Fig. 5 represents the fusible link or coupling, and Fig. 6 represents a modification in which the screw passes 40 through the side of the frame.

1 is a frame, in the upper bar of which is sustained a screw-threaded pipe-socket, 2, and nozzle 3, through which the fluid to be sprinkled passes. The form of the frame may 45 be varied without materially affecting other parts of the device, it being only essential so far as they are concerned that they be held in proper relation to each other.

4 is an angular enlargement on the pipe or 50 tube adapted to the application of a tool in

screwing the device into end of a pipe or pipe-coupling, which may connect with an extended pipe or system of pipes, which system may be either normally filled with fire-extinguishing fluid, or may be normally empty, but in such 55 relation to a holder of a supply of fluid that the pipes can readily or automatically be filled therewith in any usual way.

5 indicates a valve having, preferably, in its upper surface a ring, 6, of soft metal, rubber, or other material adapted to form a watertight joint when the valve is pressed against the nozzle. The end of the nozzle and the bearing-surface on the valve may be ground and fitted to produce a tight joint without the 65 use of a packing-ring.

7 indicates a hollow hub or extension of the valve-body which fits upon the upper end of the screw 8, the connection being such that the valve revolves as the screw is turned. In 70 the present instance this effect is secured by the angular socket in the hub fitting on a similarly-shaped post or extension, 9, of the screw-body.

The screw 10 works in a screw-threaded 75 tube, 11, formed in the lower bar of the frame, and is used to move the valve to and from its seat on the end of the nozzle. On the lower end of the screw 10 is adjustably secured a lever, 12, in any convenient manner, as by a 80 tubular enlargement, 13, rigidly held to the screw body or head by means of a set-screw, as indicated in the drawings.

14 is a bell-crank lever having its fulcrum preferably on the extension 15 of the frame. 85 One end of the lever 14 is weighted or made heavy, as indicated, and the other bent to lie when properly adjusted in the same plane and parallel with a projection or extension, 16, of the frame. The lever 12 can also be placed in 90 the same plane and adjacent to the projection 16, and the parts are so constructed and are to be so adjusted that when the valve is tightly closed against the nozzle the end of lever 12, projection 16, and the bent end of lever 14 lie 95 in one plane, and so that a link, 17, can be made to embrace them all and hold them in fixed relation to each other.

A convenient form of link is represented in the drawings. It is made of two pieces, 18 18, 100

soldered together with fusible solder to produce the form represented. The particular form is, however, not essential to the operation of the other parts of the device. The lateral extensions of the pieces adapt them to be soldered together, and in the completed link they expose a large surface to receive and conduct heat. It will be evident that the extensions of the pieces 18 allow a considerable amount of solder to be used in a thin film or layer, and that such thin layer will melt quickly and yet by its lateral extension will make a secure connection.

No fusible link known to us provides means analogous to our extensions 21 for enlarging the sensitive area of said link. These extensions being made of thin metal are quickly affected by a rise in temperature. They not only render it practicable to use a very thin film of solder, but as they extend outward away from the body of the link and away from the mass of highly-conductive metal of which the lever and connected parts are composed they are on this account less subject to loss by conduction of any heat imparted to them from the surrounding atmosphere.

As illustrated, the above-described extensions form an angle with that part of the link that is adapted to embrace movable parts or levers together with a fixed projection. They do not therefore come in contact with the parts embraced by the link, being directed away from the same, and, further, they are only connected with the body of the link at one end, the opposite end being in contact with air only and at a point removed from the link proper. It results from this construction that no conduction by metal can occur except along the length of the joint and through the small area of metal at the angle. If, also, the link is placed so that the joints lie in a horizontal plane, there is no danger that the solder when partly melted will run down upon the levers and projection and be there chilled by conduction, so as to harden upon them and prevent the desired movement of the levers, and, further, the form of the pieces composing the link illustrated is such that when unsoldered neither of them can ever embrace the levers and projection on more than two sides, or in manner to hinder their free movement.

In use the valve is raised and pressed against the nozzle by properly revolving the screw. The lever 12 having been suitably adjusted by means of the set-screw, the fusible link is placed over the ends of the levers and projection 16, as stated, in which position of the parts the weighted end of the lever 14 tends to fall and revolve the lever about the fulcrum or pivot 15. The link 17, made and described, will be melted and the parts separated by any dangerous or abnormal degree of heat, as upon the occurrence of fire in the vicinity of the device. The removal or melting of the link 65 releases the bent lever, so that the weight causes it to revolve, and it is so shaped and proportioned that it will in falling strike the

lever 12 with sufficient force to turn the screw and move the valve away from the nozzle. The momentum of the weighted arm may be sufficient to run the screw down until it is arrested by the enlargement 19, or, if not sufficient, the impact of the fluid escaping from the nozzle will effect that result. The buckets 20, formed in the upper face of the distributor 75 contribute to this operation, and after the distributor has moved to a fixed position they act to spray the water or other fluid.

In the modification shown in Fig. 6 the screw passes through the side of the frame in a direction at right angles to the direction of the nozzle and pipe connection. The lever 12 depends from the screw and can be locked to the projection 16 by a link, as in the form first described. This screw is connected by a 85 swivel or swiveled link and chain with a toggle-lever, and mediate with the valve-sprinkler, the parts being arranged, as shown, so that the screw and chain hold the toggle-lever and press the valve to its seat against 90 hydrostatic pressure. When the link is melted or otherwise removed, the pressure in the pipe and the weight of the valve will be sufficient to bend the lever at the joint, revolve the screw, and force the valve to its lowest position on the projections 21 of the frame. 95

It will be understood from the above description that the valve will be quickly and surely moved upon the melting of the link or the solder that fastens together its parts, and also that the unbroken link can be readily removed to cause the operation of the sprinkler. It is also obvious that the fluid-pressure does not bear directly upon a fusible joint or link, nor upon levers directly connected with such link, but that a screw is interposed whereby the link or joint is protected from any injurious pounding or pressure in the pipes, such pressure being necessarily applied and sustained by the inclined plane of the screw. 100 105 110

Having thus described our invention, what we desire to claim and secure by Letters Patent is—

1. In an automatic sprinkler, the combination of the nozzle, the valve and distributor, the frame provided with a screw-threaded socket, the screw working in said socket, and the arm adjustably secured to the head of the screw, substantially as set forth, whereby the valve may be closed and the arm adjusted. 115 120

2. In an automatic sprinkler, the combination of the nozzle, the valve and distributor, frame, screw, arm adjustably secured to the head of the screw, weighted bell-crank, and fusible link, substantially as specified, whereby upon the fusing of the link the weight will fall against the arm and by its momentum move said arm to open the valve. 125

3. The combination of the frame, nozzle, valve and distributor, screw, adjustable lever, projection 16, weighted bell-crank, pivot, and fusible link, all substantially as set forth. 130

4. The combination of the pipe, frame, nozzle, valve and distributor, an extension of the

valve adapted to rotate with the valve, and provided with an inclined plane having a bearing upon a similar plane, along which it moves when the valve is rotated, and the valve-operating lever, all substantially as set forth.

5. In combination with a device for automatically sprinkling and with parts arranged to be held by a link, the link made of pieces 18 18, having parts 21 soldered together by to easily-fusible material and extended or directed away from the body of the link and from the parts inclosed thereby at an angle thereto, substantially as specified, whereby the conductive action of the metallic parts held 15 by the link is diminished.

6. The link made of pieces 18 18, having extensions 21, secured together by fusible solder, the extensions of joints being directed away at an angle from the body of the link 20 and from the metallic parts inclosed thereby and arranged in a horizontal position not over said parts, in combination with the arm and projection 16, and with the valve, substantially as specified, whereby the conductive action 25 of the metal of the arm and projection is diminished and the dropping of molten solder upon the arm and projection is obviated.

7. The link for use in combination with the movable parts of an automatic sprinkler, consisting of pieces secured together with easily-fusible solder applied to extensions of said pieces directed at an angle away from the body of the link, whereby the conductive action 30 of the body of the link upon the soldered joint is diminished, substantially as set forth.

8. The combination of a fluid-conveying pipe, a frame provided with a nozzle which forms a continuation of the pipe-conduit and terminates in a valve-seat, and provided also 40 with a pivot which forms an axis for a weighted lever, and provided with an extension for securing an arm adapted to move a valve to and from said seat, the weighted lever arranged to fall against a valve-operating arm, the arm

and a fusible link for holding the arm to the 45 extension, and a valve, substantially as specified.

9. For use in an automatic sprinkler, a frame provided with a nozzle whereby it may be united to a fluid-conduit, said nozzle having 50 a valve-seat, a valve and distributor provided with an extension adapted to be supported in and moved through the frame, a valve-moving arm adapted to be connected to the frame by a fusible link, and a weighted lever pivoted to 55 the frame and arranged to fall and strike the arm upon the melting of the fusible link, substantially as specified.

10. The combination, in a frame adapted for use with a fluid-conveying pipe and with a 60 valve and distributor, of a weighted lever, a valve-operating arm, and a fusible connection between the lever and frame and also between the arm and frame, whereby when the fusible connection is melted the weighted arm 65 moves and strikes the arm to open the valve, substantially as specified.

11. The combination of a fluid-conveying pipe, a nozzle in the frame, forming a continuation of the pipe-conduit and provided with a 70 valve-seat, a combined valve and distributor normally supported against the valve-seat, an extension of the valve having a screw-threaded connection with a correspondingly-threaded socket in the frame, and a fusible link and 75 intermediate connections by which the valve is held to its seat, substantially as set forth, whereby the fluid-pressure may normally be sustained by the inclined plane along which the bearing part moves when the valve is being opened.

In testimony whereof we affix our signatures in presence of two witnesses.
